ATTACHMENT FOR BUTCHERS' MEAT BLOCKS

Filed Feb. 5, 1927

Patented June 18, 1929.

UNITED STATES PATENT OFFICE.

ANTHONY T. REED, OF PRATT, KANSAS.

ATTACHMENT FOR BUTCHER'S MEAT BLOCKS.

Application filed February 5, 1927. Serial No. 166,203.

This invention relates to an attachment for butchers' meat blocks and more particularly to a device for preventing contact of meat with the sides of the block.

5 A further and more specific object of the invention is to provide a removable apron having means whereby it may be attached to the sides of the meat block to cover the same and prevent contact of meat therewith.

10 A still further object of the invention is to provide a device of this character which may be very readily attached to the block and removed therefrom which is free from metallic fasteners which will rust or be otherwise destroyed when the apron is laundered, and which is reversible, so that its effective use while presenting a pleasing appearance, is extended.

These and other objects I attain by the construction shown in the accompanying drawings, wherein for the purpose of illustration is shown a preferred embodiment of my invention and wherein:—

Figure 1 is a side elevation showing a meat block having an apron attached thereto in accordance with my invention;

Figure 2 is a side elevation of the apron detached;

Figure 3 is a section on the line 3—3 of Figure 1;

Figure 4 is a detail side elevation of one of the attaching elements;

Figure 5 is an enlarged detail view illustrating the manner of forming the pocket.

35 Referring now more particularly to the drawings, the numeral 10 designates a strip of material of required dimensions, the edges of which are oppositely reverted, as at 11, and stitched by stitching 12, which at uniformly spaced intervals, is offset, as indicated at 13, so that the edge of the reverted portion is left free from the body of the material and a pocket 14 is provided. One of these pockets occurs at one end of each of the reverted portions and the corresponding end of the other of the reverted portions is formed with an opening 15, the purpose of which will presently appear.

To the meat block 16 at spaced intervals about the periphery thereof and adjacent the top of the side walls, I secure a plurality of fasteners 17, each in the form of a body 18 having an opening for the passage of a securing element 19 whereby it may be secured to the block and an offset tongue 20 extending upwardly from this body in parallel relation

to the block. These tongues are adapted to enter the pockets 14 formed along one edge of the apron or to pass through an opening 15 formed in one end of the apron.

60 In applying the apron, the opening 15 is engaged with one of the tongues and then the tongues engaged in their respective pockets until the apron encircles the block. The end pocket will align with the tongue which has been passed through the opening at the opposite end of the apron, so that the ends of the apron will overlap and completely protect the block. When the upper portion of the apron becomes soiled, the apron can be 70 removed and inverted, concealing the soiled portion from view and presenting a clean surface for contact with the meat.

Since the construction hereinbefore set forth is capable of a certain range of change 75 and modification without materially departing from the spirit of the invention, I do not limit myself to such specific structure except as hereinafter claimed.

I claim:—

1. An apron for a support comprising a strip of material adapted to encircle the support and having its edges oppositely reverted, stitching securing the reverted edges along their margins to the body of the material, said stitching being offset at spaced intervals to thereby produce pockets for engagement with fasteners carried by the support.

2. An apron for a support comprising a strip of material adapted to encircle the support and having its edges oppositely reverted, stitching securing the reverted edges along their margins to the body of the material, said stitching being offset at spaced intervals to thereby produce pockets for engagement with fasteners carried by the support, there being an opening extending through the body of the material and the reverted portion thereof at each end of the apron, one of the openings being formed in each reverted portion, the corresponding portion of the other of the reverted portions at each end of the apron being formed to provide one of said pockets.

3. An apron for a butcher's meat block which has a circumferential series of fasteners encircling the same, said apron comprising a strip of material having at its opposite edges and upon opposite faces thereof means for supporting engagement with said fasteners.

4. An apron for a support comprising a strip of material adapted to encircle the sup-

port and having one edge thereof reverted, stitching securing the reverted edge along its margin to the body of the material, said stitching being offset at spaced intervals to thereby produce pockets for engagement with fasteners carried by the support.

5. An apron for a support comprising a strip of material adapted to encircle the support and having one edge thereof reverted, stitching securing the reverted edge along

its margin to the body of the material, said stitching being offset at spaced intervals to thereby produce pockets for engagement with fasteners carried by the support, there being an opening extending through the body of 15 the material and the reverted portion at one end of the apron.

In testimony whereof I hereunto affix my signature.

ANTHONY T. REED.
